UNITED STATES PATENT OFFICE.

WIRT STANLEY QUIGLEY, OF PHILADELPHIA, PENNSYLVANIA.

DROP-CYLINDER FOR VAPOR-LAMPS.

SPECIFICATION forming part of Letters Patent No. 665,129, dated January 1, 1901.

Application filed September 14, 1899. Serial No. 730,434. (No model.)

To all whom it may concern:

Be it known that I, WIRT STANLEY QUIGLEY, a citizen of the United States of America, and a resident of Philadelphia, county of Philadelphia, and State of Pennsylvania, have invented certain new and useful Improvements in Drop-Cylinders for Vapor-Lamps, of which the following is a specification.

My invention relates in general to vapor-lamps; and more specifically it consists of an improved apparatus for facilitating the preheating of the vaporizing apparatus and the protection of the incandescent mantles frequently used upon this kind of lamp.

To this end the apparatus consists of a cylinder adapted to telescope up into the chimney of the lamp when the same is in regular operation and to drop down so as to surround the incandescent mantles when the lamp is put out or when it is being started into operation.

The preferred form of apparatus embodying my invention is illustrated in the accompanying two sheets of drawings, in which—

Figure 1 is a vertical section of the lamp on line 1 1 shown in Fig. 2, parts of the lamp on the left-hand side being broken away instead of being shown in section. Fig. 2 is a side elevation of the lamp shown in Fig. 1 with some of the upper parts broken away.

Throughout the drawings like reference-figures refer to like parts.

The lamp illustrated is one of the species of lamps known as "cluster-lamps," having a plurality of burners 1 1, each provided with an incandescent mantle 2 2 of the usual Welsbach type. These burners are supported from a suspended framework having a cylindrical metal chimney 3 and a hemispherical glass globe 4. A vaporizing-tube 5 extends through and across the chimney above the burners and mantles, said vaporizing-tube having a connection 5^a with the source of oil-supply.

(Not shown.) The vaporizing-tube 5 usually has a V-shaped saddle 6 supported over it for the purpose of concentrating the heat upon it, and said saddle may be lined with asbestos or other incombustible material, as shown at 6^a. This saddle 6 is supported from the lower end of the hanging rod 9, by which the entire lamp is suspended.

Within the chimney 3 is arranged a short metal cylinder 7, adapted to telescope into the chimney, as shown in full lines, or to drop down below it into the position shown in dotted lines. (See Fig. 1.) This telescoping cylinder 7 has a cross-piece 8 extending diametrically across and preferably slightly above its upper end, said cross-piece being preferably made in the form of the bent rod shown. This bent rod has its central portion 8^a coiled about the suspension-rod 9, so as to slide up and down on and be guided by said suspension-rod.

A crank-shaft 10 is journaled in the upper portion of the chimney 3 and extends across the same a little to one side of the center thereof, so as to clear the suspension-rod 9. The central bent or crank portion 11 of this crank-shaft cooperates with the cross-piece 8 of the telescoping cylinder by bearing on the under side thereof, and when said crank is in its uppermost position, as shown in Fig. 2, it drops into the small recess 16, formed on the under side of said cross-piece by the curvature given thereto. The crank-shaft 10 extends outside of the chimney and is provided with a handle 12 or other means for giving it a partial rotation. The telescoping cylinder 7 has vertical slots 13 13 formed therein, through which the vaporizing-tube 5 passes and which permit of the up-and-down motion of said cylinder above referred to.

A bridge-piece 14 extends diametrically across the upper portion of the lamp-chimney and is fastened to the suspension-rod 9 in any convenient manner, thereby affording means for supporting the lamp from said suspension-rod, as best shown in Fig. 2. An ordinary cap or deflector 15 is mounted above the chimney, and a piece of wire-gauze 17 bridges over the space between said deflector and the top of the chimney.

The mode of operation of my invention is as follows: When the lamp is in regular operation, the parts are as shown in full lines in the drawings. When the operator desires to put out the lamp in the ordinary manner by shutting off the supply of oil, he may first drop the telescoping cylinder 7 by turning the handle 12, so that the parts will assume the position shown in dotted lines in Fig. 1. This protects the mantle 2 2 and leaves the

parts in the proper position for starting up the lamp. When the lamp is started into operation, the vaporizing-tube 5 of course has to be preheated by any one of a variety of means commonly used in these lamps, such as a flame of alcohol-vapor or of a heating gas-burner, (none of such means being shown in the drawings, however,) and the position of the telescoping cylinder 7, as shown in dotted lines, assists materially in extending the degree to which the parts of the lamp surround and inclose the vaporizing-tube 5, so that the heating-flame is concentrated more closely upon the vaporizing-tube 5 and protected from side drafts and other causes which might tend to dissipate the heat. Although the preheating-flame from the gas-burners or other source heats the vaporizing-tube to the necessary temperature before oil is admitted, the other parts of the lamp still remain comparatively cool, and the initial jet of vaporized oil is thus discharged into a cold mixing-tube, where it is mingled with a body of comparatively cold air and the partly-chilled mixture passes up through a cold burner under a cold mantle. The result of this is to render the initial flow of combustible mixture from the vapor-burner somewhat feeble and to produce a tendency to condensation in the lower end of the mixing-tube. The cylinder 7 when in its lowered position serves to promote the initial operation of the lamp by throwing down upon the burners and mantle a portion of the heat of the preheating-flame. When the oil is turned on and the vapor begins to issue from the burners 11, the cylinder 7 also assists in leading said stream of vapor directly upward to the vaporizing-tube, where it is ignited by the preheating device, and the heat generated by said burners is also conducted directly to the vaporizing-tube until the lamp reaches the stage of perfect operation. Thus the cylinder 7 serves to shorten the transition period from the operation of the lamp by the preheating-burner to its self-supporting operation from the vapor-burner, reduces the tendency to condensation of oil during the starting operation, and prevents the tendency of the lamp to smoke during this period. The crank-shaft 10 is then given a partial rotation by the handle 12, so as to telescope the cylinder 7 up into the chimney, where it disappears from view, and the crank portion 11 drops into the depression 16 and is retained in its elevated position until a positive force is again applied to the crank-shaft to drop it down again and also the cylinder.

The advantages of the invention are those previously described in the protection of the mantles and the concentration of the heat upon the vaporizing-tube during the operation of starting up the lamp, and also the fact that the internal cylinder 7 when in its raised position acts as a lining for the chimney, protecting the other parts of the lamp from the great heat produced and also pre-

venting in part the radiation of said heat through the chimney. This of course tends to increase the draft of the lamp and renders its operation more perfect.

It is evident, of course, that various changes could be made in the details of construction illustrated without departing from the spirit and scope of the invention so long as the general relative arrangement of parts or the principle of operation is preserved. Other means for raising and lowering the telescoping cylinder and guiding the same in its movements might be substituted for those shown. The invention might be applied to other forms of lamps and then the various details of construction of the cylinder varied to suit such other forms of lamp; but all such changes I consider matters of form and not of substance and as not taking the modified construction outside of the scope of my invention.

Having therefore described my invention, what I claim as new, and desire to protect by Letters Patent, is—

1. In a vapor-burning lamp the combination of the lamp frame and chimney, the burners, the vaporizing-tube extending across the chimney above the burner, the inner cylinder telescoping into said chimney, and means for raising and lowering said inner cylinder.

2. In a vapor-burning lamp the combination of the lamp frame and chimney, the burners, the vaporizing-tube extending across the chimney above the burner, the inner cylinder telescoping into said chimney, and means for raising and lowering said inner cylinder, together, said cylinder being provided with vertical slots through which the vaporizing-tube passes.

3. In a vapor-burning lamp the combination of the lamp frame and chimney, the burners, the vaporizing-tube extending across the chimney above the burner, the inner cylinder telescoping into said chimney, and means for raising and lowering said inner cylinder; said means comprising a cross-piece extending diametrically across the upper end of the inner cylinder, and a crank-shaft journaled in the upper portion of the chimney and co-operating with said cross-piece.

4. In a vapor-burning lamp the combination of the lamp frame and chimney, the burners, an incandescent mantle supported over each burner, a vaporizing-tube extending across the chimney above the mantles, the bridge-piece extending across the chimney near the top thereof, the hanging rod connected to said bridge-piece, the inner cylinder arranged to telescope into said chimney, a cross-piece extending diametrically across the inner cylinder and having a sliding connection with the hanging rod, the crank-shaft journaled in the upper portion of the chimney and bearing on the under side of the cross-piece, and means external of the chimney for giving said crank-shaft a partial rotation.

5. In a vapor-burning lamp the combina-

- tion of the lamp frame and chimney, the burners, an incandescent mantle supported over each burner, a vaporizing-tube extending across the chimney above the mantle, the bridge-piece extending across the chimney near the top thereof, the hanging rod connected to said bridge-piece, the inner cylinder arranged to telescope into said chimney, a cross-piece extending diametrically across the inner cylinder and having a sliding connection with the hanging rod, the crank-shaft journaled in the upper portion of the chimney and bearing on the under side of the cross-piece, and means external of the chimney for giving said crank-shaft a partial rotation, the above-described cross-piece being so shaped as to present a recess on its under side into which the crank-shaft may drop when the cylinder is in its uppermost position.
6. In a vapor-burning lamp the combination of the lamp frame and chimney, the burners, the inner cylinder telescoping into said chimney, and means for raising and lowering said inner cylinder; said means comprising a cross-piece extending diametrically across the upper end of the inner cylinder, and a crank-shaft journaled in the upper portion of the chimney and coöperating with said cross-piece.
7. In a vapor-burning lamp the combination of the lamp frame and chimney, the burners and incandescent mantle supported over each burner, the bridge-piece extending across the chimney near the top thereof, the hanging rod connected to said bridge-piece,

the inner cylinder arranged to telescope into said chimney, a cross-piece extending diametrically across the inner cylinder and having a sliding connection with the hanging rod, a crank-shaft journaled in the upper portion 40 of the chimney and bearing on the under side of the cross-piece, and means external of the chimney for giving said crank-shaft a partial rotation.

8. In a vapor-burning lamp the combination of the lamp frame and chimney, the burners, an incandescent mantle supported over each burner, the bridge-piece extending across the chimney near the top thereof, the hanging rod connected to said bridge-piece, 50 the inner cylinder arranged to telescope into said chimney, a cross-piece extending diametrically across the inner cylinder and having a sliding connection with the hanging rod the crank-shaft journaled in the upper portion of the chimney and bearing on the under side of the cross-piece, and means external of the chimney for giving said crank-shaft a partial rotation, the above-described cross-piece being so shaped as to present a 60 recess on its under side into which the crank-shaft may drop when the cylinder is in its uppermost position.

Signed by me at Philadelphia, Pennsylvania, this 8th day of September, 1899.

WIRT STANLEY QUIGLEY.
